FRED A. DENNETT, OF SHEBOYGAN, WISCONSIN.

DESIGN FOR A BENT-WOOD CHAIR-SEAT.

SPECIFICATION forming part of Design No. 28,611, dated May 10, 1898.

Application filed February 13, 1898. Serial No. 670,867. Term of patent 14 years.

To all whom it may concern:

Be it known that I, FRED A. DENNETT, a citizen of the United States, residing at Sheboygan, in the county of Sheboygan and State of Wisconsin, have invented and produced a new and original Design for a Bent-Wood Chair-Seat; and I do hereby declare the following to be a full, clear, and exact description of the same, reference being had to the accompanying drawings, forming a part thereof.

In the said drawings, Figure 1 is a longitudinal central vertical section, Fig. 2 an under side view, and Fig. 3 a top plan view, of a bent-wood chair-seat embodying my new design.

My design relates to the new and original shape or configuration of the article.

The leading or essential feature consists in the unitary design for a bent-wood chair-seat made the subject of illustration, comprising the peculiar and novel shape of the supporting-frame for the bent-wood top, in connection with the shape of said top, which latter, except at the rear, is of substantially the same shape as in my prior patent for a design for a bent-wood chair-seat granted to me on the 31st day of August, 1897, and numbered 27,595.

Referring first to the shape of the top, as shown in central longitudinal section in Fig. 1, the said top A is first curved downward and forward on a shallow or gradual concave line, forming the arc of a large circle, from the point *a* to the point *b*, and thence continued forward on the line of a very shallow ogee to the point *c*, and then finally carried down and around on an abrupt curved convex line to the point *d*, forming the arc *c d* of a much smaller circle than that of the arc *a b* first named, this being precisely the same as in my prior design patent hereinbefore named, but the rear end of the said top A, between the points *e e*, (shown in Fig. 3,) instead of following a very slightly curved line, as in my said former design, forms the half of an ellipse in outline, as clearly shown in said Fig. 3.

The side pieces B B of the supporting-frame are vertical and straight on their outer edges from their front ends, beginning with the points *f f*, Fig. 2, to the points *g g*, and on their inner edges are straight between the points *h h* and *i i*. From the points *i i* to the

points *j j* the said inner edges are formed on curved lines, while from the points *j j* to the points *k k* the said inner edges are formed on straight lines parallel with the straight lines between the points *h h* and *i i* just described. The upper surfaces of the side pieces B B conform in shape exactly to the shape of the top A, and the under surfaces of said side pieces B B likewise conform to said shape from the rear point *o* as far forward as the point *q*, (see Fig. 1,) while between the points *q r* the said under surfaces are formed on the lines of short ogees, and from the point *r* to the extreme front point *s* the said under surfaces are formed on practically straight lines, slightly inclining downward from rear to front. The inner edges of said side pieces B B are formed on concave rounded lines from the points *h* to the points *t*, and from the points *t* to the points *u* said inner edges are formed on straight vertical lines parallel with the straight lines of the corresponding portions of the outer edges of said side pieces.

The rear piece C of the supporting-frame is formed on curved lines between the points *k k* on the outer edge and the points *v v* on the inner edge, the curved lines corresponding to the curvature of the line of the top A between the points *e e*, though being shorter. The upper surface of the piece C is transversely rounded on the arc of a circle and corresponds in shape exactly to the shape of the top A between the points *a n*, as shown in Fig. 1. Further, the outer edge of the piece C is not vertical, but is beveled or inclined inward and downward, as indicated by the outer curved line at the right-hand end of Fig. 2 and, as further shown, by the line between the points *a o* at the right-hand end of Fig. 1, while the inner edge of the said piece C is similarly inclined, as indicated by the line between the points *n p* in Fig. 1.

Minor features of my said design include the stoppage of the circular inner line of the rear piece C at the points *v v* and forming the ends of the inner edge of said piece on straight lines between the points *v w* at each end, as shown in Fig. 2, as well as inclining these straight portions upward and forward, as indicated by the line *v m* in Fig. 1; also, the form of the front rod D of the supporting-

frame in the shape of a cylinder, as shown in Figs. 1 and 2.

Having described my invention, what I claim as new, and desire to secure by Letters

5 Patent, is—

The design for a bent-wood chair-seat, substantially as herein shown and described.

In testimony whereof I affix my signature in presence of two witnesses.

FRED A. DENNETT.
